UNITED STATES PATENT OFFICE.

APOLOS P. AMES, OF TACOMA, WASHINGTON.

FOUNTAIN-SYRINGE.

1,374,799.

Specification of Letters Patent. Patented Apr. 12, 1921.

Application filed May 16, 1917. Serial No. 169,024.

To all whom it may concern:

Be it known that I, APOLLOS P. AMES, a citizen of the United States, residing at Tacoma, in the county of Pierce and State of Washington, have invented certain new and useful Improvements in Fountain-Syringes; and I do hereby declare the following to be a full, clear, and exact description of the invention, such as will enable others skilled in the art to which it appertains to make and use the same.

This invention relates to improvements in fountain syringes.

The object of this invention is to provide means, by which any ordinary fruit jar, bottle or the like may be substituted for rubber bags or reservoirs now commonly in use in such syringes.

A still further object of this invention is to provide a novel cap, which is equipped within a supporting means and an outlet to which a rubber tube may be connected and has an air inlet, and this cap may be readily secured to a suitable jar, bottle or the like, thus constituting a fountain syringe.

A still further object of this invention is to provide a fountain syringe of this character, which will be simple, practical and comparatively inexpensive in construction.

With these and other objects in view, the invention consists in the novel combination and arrangement of parts hereinafter more fully described and set forth in the claims hereto appended.

In the drawings:

Figure 1 is a rear elevation illustrating my improved fountain syringe as made in accordance with this invention.

Fig. 2 is a vertical sectional view taken on the line 2—2 of Fig. 1.

Fig. 3 is a side elevation of my improved cap as made in accordance with this invention.

Like numerals of reference designate corresponding parts in all the figures of the drawings.

Referring to the drawings, the numeral 1 indicates a bottle or jar of the ordinary construction having a neck 2, which is provided with exterior screwthreads 3.

My improved invention comprises in its construction, a cap 4, which has an interior screwthreaded annular flange 5, which is adapted to be removably fitted upon the screwthreads 3 of the bottle, jar or the like.

The cap 4 is provided centrally with an opening 6, to which and around the walls of which is formed integrally the depending pipe 7, which is adapted to have removably connected thereto, one end of the tube 8. The opposite end of the tube has the usual nozzle 9 secured thereto.

The cap 4 is also provided with an opening 10, which has formed integrally around the walls thereof, the inwardly extending vertical pipe 11, which pipe has its inner end terminating at a short distance from the bottom of the bottle, as clearly shown in Fig. 2, and thus constitutes an air inlet 70 to permit the free flow of the contents from the bottle out through the pipe 7 and tube 8 when the bottle is in an inverted position.

A supporting member designated in its entirety by the numeral 12 comprises a vertical arm 13, which has its lower end bent angularly as at 14 and is adapted to be arranged in a substantially horizontal plane and has its extreme end secured to the outer side of the cap 4 as at 15, thus spacing the vertical arm 13 or arranging the same in close proximity to the wall of the jar or bottle 1.

The upper end of the supporting arm 13 extends upwardly beyond the plane of the bottom 16 of the jar 1 as at 17 and is provided adjacent its end with an opening 18, which facilitates the securing of the arm to a nail which is driven into a support for holding the bottle in an inverted position to permit its contents to run out of the tube and nozzle.

To operate the device, the cap is removed from the bottle or jar, and the bottle 1 is filled with liquid to be injected, the cap is then removably fitted on the screwthreads of the jar or bottle, the bottle or jar is then inverted and the supporting arm 13 is arranged or removably secured to a suitable support holding the bottle in an inverted position, thus permitting the liquid to run out through the pipe 7 into the tube 8 and out through the nozzle 9, it being understood that the flow of the liquid can be controlled by pressing the tube at the point indicated by the letter A, thus cutting it off or permitting it to flow freely as desired. The pipe 11 permits an inlet of air into the bottle or jar 1, thus permitting the liquid to readily flow out through the tube 8 and nozzle 9 and the arm 13 facilitates the supporting of the device to the wall so as

to obviate the necessity of holding the jar by one when the syringe is ready for an operation. When the bottle or jar is empty, it can be placed in an upright position and refilled by simply removing the cap as in the initial operation.

What is claimed is:

As a new article of manufacture, a cap having a liquid discharge pipe extended therefrom in one direction and a vent pipe extended in the opposite direction, and a suspending member carried by said cap, whereby the cap may be suspended in

inverted position with an inverted conventional liquid container such as a preserve jar 15 secured thereon in inverted position to convert the jar into a fountain syringe, the liquid discharge tube being adapted to receive a flexible nozzle carrying discharge tube.

In testimony whereof I affix my signature in presence of two witnesses.

APOLLOS P. AMES.
